UNITED STATES PATENT OFFICE.

ISADORE S. ZITLIN, OF CHICAGO, ILLINOIS, ASSIGNOR OF ONE-HALF TO MEYER ZITLIN,
OF CHICAGO, ILLINOIS.

RADIATOR.

Application filed April 1, 1920. Serial No. 370,450.

To all whom it may concern:

Be it known that I, ISADORE S. ZITLIN, a citizen of the United States, and a resident of the city of Chicago, county of Cook, and 5 State of Illinois, have invented certain new and useful Improvements in Radiators, of which the following is a specification.

My invention relates to improvements in radiators especially adapted for use on automobiles or the like, and has for its object 10 the provision of an improved construction of this character having special provisions therein for efficient air circulation, and strength and rigidity of construction, the 15 present invention being an improvement over that disclosed in my prior application filed April 21st, 1919, Serial No. 291,613.

Other objects will appear hereinafter.

The invention consists in the combinations 20 and arrangements of parts hereinafter described and claimed.

The invention will be best understood by reference to the accompanying drawings forming a part of this specification, and in 25 which,

Fig. 1, is a front view of a radiator embodying the invention,

Fig. 2, an enlarged detail horizontal partial section taken on line 2—2 of Fig. 1, 30

Fig. 3, an enlarged vertical section taken on line 3—3 of Fig. 2,

Fig. 4, an enlarged front view of a portion of the radiator proper, and

Fig. 5, an enlarged plan view of a section 35 of one of the metal sheets employed in the radiator.

The preferred form of construction, as illustrated in the drawings, comprises adjacent copper sheets 6 bent into zig-zag form 40 and arranged together in pairs in the usual way to form vertical zig-zag water tubes 7, as indicated, the forward and rear edges of each pair of sheets 6 being brought together and soldered at 8 to close the front and rear 45 sides of said water tubes. The individual tubes thus formed are also bent at their forward and rear edges at the points 7', where their zig-zag form bring them adjacent each other so as to bring the edges of the tubes 50 proper together when assembled in the radiator. The zig-zag water tubes thus formed

are secured together in the radiator in the usual way, to form horizontal air passages 9 therethrough to permit of the free passage of air through the radiator and to bring 55 the portions 7, of the forward and rearward edges of adjacent tubes into contact with each other. The forward and rear edges of the assembled radiator tubes are then dipped in solder in the usual way, to secure the tubes 60 in place, and the body thus formed is assembled into the radiator in the usual way.

The sheets 6 are provided with laterally vertically extending projections 10 and 11, arranged to register with those in adjoining 65 sheets on the opposite sides of the air passage 9, the set of ribs 11 being provided with indentations arranged and adapted to receive the corresponding projections 10 on the adjoining sheet on the opposite side of the air 70 passages, this arrangement serving to properly position the water tubes apart to permit of free vertical circulation of the air between them, and also serving to definitely position said water tubes with relation to each other 75 to facilitate the assembling thereof and also to increase the rigidity and durability of the construction. By this arrangement it will be observed that a vertical circulation of air, as well as a horizontal circulation thereof, 80 is permitted through the radiator, thus adding to the cooling efficiency thereof, and that a strong, rigid and durable construction is provided.

While I have illustrated and described the 85 preferred form of construction for carrying my invention into effect, this is capable of variation and modification without departing from the spirit of the invention. I, therefore, do not wish to be limited to the 90 precise details of construction set forth, but desire to avail myself of such variations and modifications as come within the scope of the appended claim.

Having described my invention, what I 95 claim as new and desire to secure by Letters Patent is:—

A radiator comprising adjacent sheets of material bent and secured together to form water tubes and air passages, said sheets being provided with registering inter-locking projections spanning said air passages and 100

permitting inter-communication between them, one of the projections of each registering pair being indented to receive the other of that pair, the extreme forward and rear edges of said tubes being brought and soldered together, substantially as described.

In testimony whereof I have signed my

name to this specification in the presence of two subscribing witnesses.

ISADORE S. ZITLIN.
